(**) Term: **14 Years**

(21) Appl. No.: **29/343,304****CLAIM**(22) Filed: **Sep. 10, 2009**

The ornamental design for a drug administration safety label, as shown and described.

Related U.S. Application Data

(62) Division of application No. 29/332,179, filed on Feb. 10, 2009, which is a division of application No. 29/298,328, filed on Dec. 3, 2007, now Pat. No. Des. 588,200.

DESCRIPTION

(51) **LOC (9) Cl.** 19-08

FIG. 1 is a top plan view of one embodiment of a drug administration safety label of our new design.

(52) **U.S. Cl.** **D20/27**

FIG. 2 is a top plan view of an alternative embodiment of a drug administration safety label of our new design.

(58) **Field of Classification Search** ..... D20/10, D20/11, 13, 22-27, 99; 40/124.01, 124.02, 40/124.04, 299.01, 310, 325, 360, 326, 538, 40/541, 584, 594, 600, 630, 638; D19/1, D19/9, 10; 206/63.3, 534; 235/50 A; 283/51, 283/56, 67, 71, 74, 75, 81, 99-107, 108, 283/109, 114, 117; 359/2; 428/40.1, 42.1-42.3, 428/914

FIG. 3 is a top plan view of an alternative embodiment of a drug administration safety label of our new design.

See application file for complete search history.

FIG. 4 is a top plan view of an alternative embodiment of a drug administration safety label of our new design.
